[57] **CLAIM**

The ornamental design for the aerodynamic visor-lens sunglasses, as shown and described.

DESCRIPTION

FIG. 1 is a perspective view of aerodynamic visor-lens sunglasses showing one embodiment of my new design; FIG. 2 is a front elevational view thereof; FIG. 3 is a rear elevational view thereof; FIG. 4 is a left side elevational view thereof; FIG. 5 is a right side elevational view thereof; FIG. 6 is a top view thereof; FIG. 7 is a bottom view thereof; FIG. 8 is a perspective view of aerodynamic visor-lens sunglasses showing a second embodiment of my new design; FIG. 9 is a front elevational view of the second embodiment thereof; FIG. 10 is a rear elevational view of the second embodiment thereof; FIG. 11 is a left side elevational view of the second embodiment thereof; FIG. 12 is a right side elevational view of the second embodiment thereof; FIG. 13 is a top view of the second embodiment thereof; FIG. 14 is a bottom view of the second embodiment thereof; FIG. 15 is a perspective view of aerodynamic visor-lens sunglasses showing a third embodiment of my new design; FIG. 16 is a front elevational view of the third embodiment thereof;

FIG. 17 is a rear elevational view of the third embodiment thereof;

FIG. 18 is a left side elevational view of the third embodiment thereof;

FIG. 19 is a right side elevational view of the third embodiment thereof;

FIG. 20 is a top view of the third embodiment thereof; and,

FIG. 21 is a bottom view of the third embodiment thereof.
